UNITED STATES PATENT OFFICE.

WILLIAM E. WINE, OF TOLEDO, OHIO.

CAR-DOOR MECHANISM.

Application filed October 30, 1924. Serial No. 746,813.

The invention relates to a car door mechanism for railway cars or the like and has for its object to provide simple and efficient means for insuring that the mechanism by 5 which the door is maintained in closed position shall assume proper locked relation to the door at the end of the closing movement of the latter. A more specific object of the invention is to provide a door locking mechanism of the hook type with spring means 10 adapted to be energized by a closing movement of the door to effect a locking rotation of the hook member by which the door is maintained in closed position. Another object of the invention is to provide a door locking mechanism involving a pivoted door supporting hook associated with spring means serving to exert pressure upon the hook when the door is closed, the said spring 15 means being operatively interposed between the door and the hook and adapted to be energized during the final movement of the door to closed position.

Other features of the invention residing 20 in particular relations of parts and advantageous forms of construction will herein-after appear.

In the drawings illustrating a preferred embodiment of the invention, the scope 25 whereof is pointed out in the claims,—

Figure 1 is a view in side elevation of a fragmentary portion of a car hopper showing a door locking mechanism embodying the invention applied thereto.

Figure 2 is an end view of the construction illustrated in Fig. 1.

Figure 3 is a view partly in section and partly in side elevation showing the relations assumed by the parts of the locking mechanism when the door is open and indicating in dot and dash lines the position of the locking arm of the door as the latter approaches closed position.

Figure 4 is a detail view taken on the line 45 4—4, Fig. 1.

The railway car to which the door locking mechanism embodying the invention is shown as applied is of a well known type and therefore only a portion of one of the 50 hoppers thereof has been illustrated in the drawings. The hopper portion of the car body may be constructed in the usual manner with hopper side sheets 1 and a slope sheet or chute plate 2 whose outer ends or

edges define the discharge opening of the 55 hopper. A swinging door 3, which may be hinged to the car body in any usual or desired manner, serves to close the discharge opening of the hopper. As shown in the drawings, the door 3 is preferably constructed of sheet metal and may advantageously be provided with outwardly projecting marginal flanges.

In cars of the type illustrated the doors 3 are arranged on opposite sides of the car 60 center sills and are rigidly connected by a door spreader or stiffening beam 4 so that they operate together and in effect constitute a single door. In the present instance the door spreader employed is a Z-bar member 65 5 and terminating inside of the marginal flange 6 at the outer edge of the door.

Rigidly secured to the door and to the door spreader by means of rivets 7 and 8, 70 respectively, is a door arm 9 which may advantageously be formed as an angle iron which is offset or bent outwardly from the face of the door at 10 so as to pass beneath the outer marginal door flange 6. The 75 upper standing leg or flange 11 of the door arm 9 forms a locking ledge or seat adapted to be engaged by the locking ledge or shoulder 12 of the hook member 13 to lock the door 3 in closed position. The described door construction is preferred because of its simplicity, but it is to be understood that the 80 precise details of door construction illustrated are not required to cooperate with the door locking mechanism now to be described.

Pivotedly mounted upon the car body, as by means of a rivet 14, is a door supporting hook 13 having a locking face or shoulder 12 adapted to engage and overlap the flange 11 of the door arm 9. At its outer end the hook is formed with a curved or inclined face 15 constituting an approach plane. In the closing movement of the door the upper edge of the flange 11 of the door arm engages and slides along this approach plane, thus causing the hook member 13 to rotate in an 90 unlocking direction.

The hook member 13 may advantageously be in the form of a bell crank lever whose inner arm affords a seat or abutment 16 for a coiled compression spring 17, the latter 95 preferably being housed within a cylindrical chamber 18 cast integral with the hook mem-

- ber. The outer end of the spring 17 bears against a reciprocating plunger 19 which projects outwardly beyond the discharge opening of the hopper when the door is open.
- 5 The plunger is so positioned that it will be engaged by the flange 11 of the door arm 9 as the door is swung to closed position, thus causing the plunger to be forced inwardly and compress the spring 17 carried within 10 the spring chamber of the hook member. If desired the outer end of the plunger may be provided with a roller 20. To maintain the spring 17 and plunger 19 in assembled relation to the hook 13 the plunger is preferably fashioned with a rod-like extension 21 which passes through the spring and through an opening 22 in the hook member at the base of the spring chamber and receives a split key or cotter 23 at its inner 15 end.
- The hook member 13 is preferably pivotally connected to a plate or bracket 24 having a lug or shoulder 25 adapted to cooperate with the hook member 13 so as to 20 limit the extent of the locking rotation of the latter. A locking cam 26 also is preferably pivotally mounted upon the bracket 24, a rivet 27 which passes through said bracket and the hopper side sheet 1 being 25 employed for that purpose. The hook member 13 and the locking cam 26 may advantageously be guided and the outer ends of their pivots efficiently supported by means of a plate or strap 28 overlying said hook 30 and cam and through which said rivets 14 and 28 pass. If desired a rivet 29 which passes through the bracket 24 and through the side sheet 1 of the hopper may, in addition to the rivets 14 and 27, be employed 35 to secure said bracket rigidly to the car side.
- When the door 3 is swung towards closed position the upwardly extending flange 11 of the door arm 9 comes into contact with the approach plane 15 of the hook member 40 45 13. The further closing movement of the door causes the hook 13 to perform an unlocking rotation as the door arm flange 11 travels along the approach plane 15. This unlocking rotation of the hook causes the 50 spring actuating plunger 19 to advance toward the door as the latter swings inwardly. When the roller 20 and flange 11 of the door arm come into contact, a continuance of the 55 closing movement of the door causes the spring 17 to be energized, and when the door has reached a fully closed position so that the hook 13 is enabled to rotate to locked position the spring 17 expands, thus causing the locking ledge 12 of the hook member 60 65 to overlap the flange 11 of the door arm in position for maintaining the door closed. The locking cam 26 may then be rotated into engagement with the back of the hook 13, as shown in Fig. 1. It will be observed 70 that the construction is such that the spring

mechanism not only serves to assist gravity in causing the hook 13 to assume a locked position when the door is closed, but also, in addition to the cam 26, tends to maintain the hook in locked relation to the door.

70

I claim:—

1. A railway car having an opening for the discharge of lading, a door for closing said opening, means movably mounted on the car body for engaging said door to lock 75 the latter in closed position, and means actuated by the said door and interposed between said door and said movably mounted means for causing the latter to move toward locking position.

2. A railway car having an opening for the discharge of lading, a door for closing said opening, means movable with respect to said door for securing the latter in closed position, and means actuated by the said 85 door and interposed between said movable means and said door for forcing said last named means to door securing position.

3. A railway car having an opening for the discharge of lading, a swinging door for 90 closing said opening, movable means for engaging said door to maintain the latter in closed position, and spring means mounted on said movable means and adapted to actuate the latter, said movable means being 95 adapted to cause said spring means to move toward said door when the latter is swung to closed position.

4. A railway car having an opening for the discharge of lading, a door for closing 100 said opening, movable means for releasably securing said door in closed position, and spring means adapted to actuate said movable means for forcing the latter to door securing position, said spring means including 105 a spring which is adapted to be compressed from one end by said door and to be compressed from the other end by said means for securing said door in closed position.

5. A railway car having an opening for 110 the discharge of lading, a door for closing said opening, a hook member pivotally mounted on the car body for engaging said door to lock the latter in closed position, a spring carried by said hook member and movable therewith, and a plunger mounted on and adapted to reciprocate with respect to said hook member, said plunger being adapted to be actuated by said door to energize said spring during 115 a closing movement of said door, and said spring being adapted to cause said hook member to rotate to locked position.

6. A railway car having an opening for the discharge of lading, a door for closing 125 said opening, a hook adapted to engage said door to lock the latter in closed position, and spring means mounted upon the car body and adapted to actuate said hook to force the latter to locked position,

130

said spring means being adapted to be engaged and energized by said door as the latter moves towards closed position.

7. A railway car having an opening for the discharge of lading, a door for closing said opening, means movable with respect to said door for releasably securing the latter in closed position, and spring means adapted to actuate said movable means for forcing the latter to door securing position, said spring means being adapted to be energized upon the closing movement of the door and being adapted simultaneously to engage the door and car body.

15 8. A railway car having an opening for the discharge of lading, a swinging door for closing said opening, a movable hook member adapted to secure the door in closed position, spring means carried by said hook member for forcing the latter to door securing position, said hook member and said spring means being adapted to be actuated by said door upon a closing movement of the latter, and means for limiting the door securing movement of said hook member.

25 9. A railway car having an opening for the discharge of lading, a swinging door for closing said opening, a bracket fixed with respect to the car body, a hook member pivotally connected to said bracket for releasably securing said door in closed position, said bracket being provided with a stop adapted to engage said hook member to limit the door securing movement of the latter, 30 said hook member being formed with a portion forming a spring abutment, a spring seated on said abutment, and a reciprocating plunger carried by said hook member and engaging said spring and adapted to 35 energize the latter upon a closing movement of said door.

40 10. A railway car having an opening for

the discharge of lading, a swinging door for closing said opening, a movable hook member for releasably securing said door against an opening movement, said hook member constituting a pivoted lever formed at one end with a hook and provided at the other end with an arm forming a spring abutment, a spring, and means actuated by said door for energizing said spring upon a closing movement of said hook, said spring being operatively interposed between said means and said abutment on said hook member.

11. A railway car having an opening for the discharge of lading, a swinging door for closing said opening, a hook member pivotally mounted on the car body for releasably securing said door against an opening movement, a spring chamber carried by said hook member at one side of the pivotal point of the latter, a spring within said spring chamber, a reciprocating plunger extending into said chamber and adapted to energize said spring, and means for maintaining said spring and plunger in assembled relation with said chamber, said spring being adapted to be energized by said plunger upon a closing movement of the door, whereby said hook member is caused to rotate to door securing position when the door is closed.

12. A railway car having an opening for the discharge of lading, a door for closing said opening, movable means for securing said door in closed position, and spring means interposed between said movable means and said door when the latter is in closed position, acting to maintain said movable means in position for retaining said door in closed position.

In testimony whereof I affix my signature.

WILLIAM E. WINE.
